(57) **CLAIM**

The ornamental design for a chamber for electronic atomizing device as shown and described.

DESCRIPTION

FIG. 1 is a perspective view of a chamber for an electronic atomizing device showing an embodiment of our design; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is an enlarged top plan view thereof; FIG. 8 is an enlarged bottom plan view thereof; FIG. 9 is a perspective view of a chamber for an electronic atomizing device showing another embodiment of our design; FIG. 10 is another perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is an enlarged top plan view thereof; FIG. 16 is an enlarged bottom plan view thereof; FIG. 17 is a perspective view of a chamber for an electronic atomizing device showing further another embodiment of our design; FIG. 18 is another perspective view thereof; FIG. 19 is a front elevational view thereof; FIG. 20 is a rear elevational view thereof; FIG. 21 is a left side elevational view thereof; FIG. 22 is a right side elevational view thereof; FIG. 23 is an enlarged top plan view thereof; and, FIG. 24 is an enlarged bottom plan view thereof.

The broken lines in the drawings depict portions of the chamber for electronic atomizing device that form no part of the claimed design.
